HANDLE FOR A RECIPROCATORY PISTON ROD

Linus E. Russell, Springfield, Ohio

Application September 7, 1951, Serial No. 16,554

Term of patent 14 years

(Cl. D46—1)

To all whom it may concern:

Be it known that I, Linus E. Russell, a citizen of the United States, residing at Springfield, Clark County, Ohio, have invented a new, original, and ornamental Design for a Handle for a Reciprocatory Piston Rod, of which the following is a specification, reference being had to the accompanying drawing forming a part thereof, in which

Fig. 1 is a perspective view of a handle for a reciprocatory piston rod embodying my new design;

Fig. 2 is a side view thereof; and

Fig. 3 is an end view thereof.

The dominant features of my new design are shown in full lines in the accompanying drawing.

I claim:

The ornamental design for a handle for a reciprocatory piston rod, substantially as shown and described.
